(57) **CLAIM**

The ornamental design for a twin towers cross statue, as shown and described.

DESCRIPTION

FIG. 1 is a front perspective view of a first embodiment of a twin towers cross statue.

FIG. 2 is a front elevational view of the first embodiment; the rear elevational view is a mirror image of the front elevational view.

FIG. 3 is a left side elevational view of the first embodiment; the right side elevational view is a mirror image of the left side elevational view.

FIG. 4 is a top plan view of the first embodiment.

FIG. 5 is a bottom plan view of the first embodiment.

FIG. 6 is a front perspective view of a second embodiment of a twin towers cross statue.

FIG. 7 is a front elevational view of the second embodiment; the rear elevational view is a mirror image of the front elevational view; and,

FIG. 8 is a left side elevational view of the second embodiment; the right side elevational view is a mirror image of the left side elevational view.

The top and bottom views are identical to the respective views of the first embodiment.
